Primary Examiner — Eric L Goodman*Assistant Examiner* — Catherine S Posthauer(74) *Attorney, Agent, or Firm* — Banner & Witcoff, Ltd.(57) **CLAIM**

The ornamental design for a cradle for cylindrical objects, as shown and described.

DESCRIPTION

FIG. 1 is a right front perspective view of a cradle for cylindrical objects, showing my new design;

FIG. 2 is a right side view thereof, the left side view being identical thereto;

FIG. 3 is a top plan view thereof;

FIG. 4 is a front end view thereof, the rear end view being identical thereto;

FIG. 5 is a right front perspective view of the cradle for cylindrical objects as shown from FIGS. 1-4, shown in a position of use with an exemplary support pad;

FIG. 6 is a right side view thereof, a left side view being identical thereto;

FIG. 7 is a top plan view thereof; and,

FIG. 8 is a front end view thereof, the rear end view being identical thereto.

The broken lines are shown for the purpose of illustrating environmental subject matter of exemplary support pads, as well as parts of the article, none of which form part of the claim.
